United States Patent [19] Lord

[11] Patent Number: Des. 425,969
[45] Date of Patent: ** *May 30, 2000

[54] PULL-OUT SPRAY FAUCET BODY

D. 399,927 10/1998 Doughty et al. D23/255

[75] Inventor: **Judd A. Lord**, Carmel, Ind.

Primary Examiner—Eric Watterson

Attorney, Agent, or Firm—Myron B. Kapustij; Lloyd D. Doigan

[73] Assignee: **Masco Corporation of Indiana**,
Indianapolis, Ind.

[57]

CLAIM

[*] Notice: This patent is subject to a terminal disclaimer.

The ornamental design for a pull-out spray faucet body, as shown and described.

[**] Term: **14 Years**

DESCRIPTION

[21] Appl. No.: **29/094,517**

FIG. 1 is a perspective view of a pull-out spray faucet body showing my new design;

[22] Filed: **Oct. 5, 1998**

FIG. 2 is a front elevational view thereof;

[51] LOC (7) Cl. **23-01**

FIG. 3 is a top plan view thereof;

[52] U.S. Cl. **D23/255**

FIG. 4 is a right side elevational view thereof, the left side

[58] Field of Search D23/238-243,
D23/250-257; 9/675-678; 137/801

being a mirror image;

FIG. 5 is a rear elevational view thereof; and,

FIG. 6 is a bottom plan view thereof.

The broken line showing of a pull-out spray in FIG. 1 is for purposes of illustration only and forms no part of the claimed design.
